UNITED STATES PATENT OFFICE.

JOHN W. F. MACDONALD, OF BOSTON, MASSACHUSETTS.

FURNACE-GRAVE.

1,130,303.

Specification of Letters Patent. Patented Mar. 2, 1915.

Application filed August 21, 1911. Serial No. 645,265.

To all whom it may concern:

Be it known that I, JOHN W. F. MACDONALD, a subject of the King of Great Britain, residing at Boston, in the county of Suffolk and State of Massachusetts, have 5 invented certain new and useful Improvements in Furnace-Grates; and I do hereby declare the following to be a full, clear, and exact description of the same, reference being had to the accompanying drawings, 10 forming part of this specification, and to the figures and letters of reference marked thereon.

This invention relates to furnace grates 15 and more especially to that type of furnace grate with which the fuel is supported on a plurality of rocking or oscillating sections, a number, or all of which, sections are adapted to rock simultaneously in the same 20 direction.

The objects of the invention are to provide a grate in which the fuel supporting sections will present a flat surface when at rest in normal position, and a surface of 25 maximum irregularity when operated for shaking the fire or removing the ashes and clinker, with means whereby the grate sections will be locked in normal position, and the removal of the handle or operating lever 30 prevented whenever the grate sections are in other than normal position.

A further object of the invention is to provide a grate in which a maximum movement of the sections may be obtained without 35 unduly increasing the size of the openings between the sections and at all times unrestricted air passages will be left for the direct admission of air to the fuel.

A further object of the invention is to 40 provide an improved form of rocker bar and removable fuel supporting grate sections adapted to be mounted upon and be moved in unison with the rocker bars, the distribution of the metal in the bars being 45 such as to give the greatest strength possible in proportion to the weight of metal employed.

With these objects in view, the invention 50 consists in certain novel details of construction and combinations and arrangements of parts, all as will be now described and pointed out particularly in the appended claims.

Referring to the accompanying drawings,—Figure 1 is a sectional view showing 55 a grate embodying the present improve-

ments, partly in side elevation and with parts broken away and in section; Figs. 2 and 3 are diagrammatic sectional elevations illustrating the action of the locking mechanism for the grate sections and operating handle or lever; Fig. 4 is a top plan view of the mechanism shown in Figs. 2 and 3; and Fig. 5 is a detail view of the arm carried by the rocker bar and the link.

Like letters of reference in the several figures indicate the same parts.

The grate in which the present invention is embodied, comprises in the form illustrated, front and rear or end bearer bars A upon which the center and side bearer bars B and C are supported so as to form a more or less rectangular framework of conventional form and which, it will be understood, may be of any form in which grates 70 of the character to be presently described may be employed, the form of the grate frame, of course, conforming to the style of fire box, as will be readily understood. The employment of a center bearer bar presupposes the extension of the grate surface on both sides of it, but of course in small grates but two side bearer bars would be employed. Each of the bearer bars B and C is provided with bearings c for the journals d 80 of rocker bars D, said journals d being located near the upper edge of the rocker bars D and preferably slightly to one side of the central plane of said bars, as best seen in Fig. 1. The upper edges of the rocker bars D, intermediate the journals, are preferably substantially flat and of regular outline, as best seen in the sectional portion of Fig. 1, the major portion of the metal in said bars being disposed in the lower part 85 of the bars and the width of the bar centrally being and the width of the bar centrally being made greater than at the ends, whereby the metal is distributed so as to give the greatest strength for the weight of metal employed. The disposition of the metal 90 will be appreciated, when it is remembered that these rocker bars are made of castiron which is comparatively strong under compression, but comparatively weak under tension strains, and therefore the greatest 95 cross sectional area should be disposed in the line of tension strains.

The grate sections E, each of which may be relatively short, are in cross sectional outline, substantially equilateral triangles, one 110 of the flat faces being formed with the usual fuel supporting bars and cross pieces and

being adapted to normally lie in substantially horizontal position, as shown in full lines in Fig. 1, to form the fuel supporting surface. One of the other faces is formed with ribs which are adapted to form fuel supporting or clinker and ash engaging surfaces, only when the grate is moved in the shaking operation, as, for instance, when the sections are turned up into the position indicated in dotted lines, in Fig. 1, which dotted lines indicate the extreme movement in one direction, while the full lines indicate the extreme movement in the opposite direction of the several grate sections.

In grates of this type it has been found that the greatest range of oscillation which can be successfully employed is about 60°, and in the present invention it is designed that one extreme of this movement shall leave the flat fuel supporting surfaces of the sections substantially horizontal, and with the rocker bars slightly inclined, the general plane of the inclination to the horizon being about 60°. In other words, with a grate section of equilateral triangular form, in which one flat face forms the normal fuel supporting surface, the socket for the reception of the edge of the rocker bar extends substantially parallel with one of the other faces of the section. This arrangement permits of a maximum movement of the grate sections, and the formation of a maximum irregularity during such movement, with a substantially uniform space or opening between the sections. For instance, when the sections are in normal position the spaces between them are substantially the same as the spaces between them when they are turned to the opposite extreme of their movement, as shown in the dotted lines, Fig. 1, and consequently, there is at no time opportunity for the escape of unburned fuel between the sections and into the ash pit. At the same time the points of the triangles penetrate deeply into the body of the fire, allowing the air to circulate freely to the fuel, so as to give a maximum efficiency and to afford the maximum capacity of the sections for discharging ashes and clinker. Owing to this construction also, the grate sections may be made somewhat shorter than is usual and consequently have a greater leverage or power for breaking up clinker, without unduly increasing the range of movement of the rocker bars and operating connections. Each grate section may be separately removed from its rocker bar and others substituted for renewal purposes; or, in case the character of fuel used be changed, all of the sections may be changed to suit the particular fuel to be used. At the front and rear of the grate, headers F are provided having the usual transverse projections for supporting the end portions of the body of

fuel. The headers at their ends are formed with hook-shaped projections, adapted to seat in correspondingly shaped seats or recesses in the ends of the beater bars B and C.

Each of the rocker bars D is provided with a downwardly extending arm D' and a connecting bar H serves to connect all of the arms for simultaneous oscillatory movement. Pivotally secured to the connecting bar H is an arm or casting h and to this arm is connected the inner end of link I, which extends through an aperture in the front wall of the furnace, and at its outer end is pivotally connected with the depending portion or arm k of the bell crank lever K. In order to allow for the difference in the thickness of the wall of the furnaces, the connection between the inner end of the link I and arm h is made adjustable. For this purpose the arm h is formed with a series of openings h', and the link I with a series of openings i', which may be brought into registry with the holes in the casting, and the two held together by means of a bolt or other fastening means. In order that there may be a fine adjustment over a wide range the holes in the arm are equally spaced, as are the holes in link I, but the distance between the center of the holes in one of these members is not the same as the distance between centers in the other member. As shown in the drawings, there are seven holes in the casting and nine holes in the link, and the distance between, from center to center of every third hole in the casting, is the same as the distance from center to center of the fifth hole in the bar. By such an arrangement an adjustment can be made as fine as the difference between centers of adjacent holes.

The bell crank K is pivotally mounted in a bracket L secured to the front wall of the furnace and is socketed for the reception of a shaking lever or operating handle M. The socket is usually rectangular in cross section so that the handle can only be entered therein when properly positioned with relation to the bell crank, and provision is made whereby the handle or lever cannot be removed from the bell crank unless and until the grate sections have been properly positioned with their fuel supporting faces horizontal and unless and until the said sections are positively locked in such position. To accomplish the aforesaid results, the bell crank K is provided with a pivoted lock O, having a grate locking projection o which is adapted to enter a recess l in the bracket L for locking the grate in its correct normal position, and a projection or cam o' for co-operating with a recess m in the shaking lever handle M for locking the latter in its socket in the bell crank, the projections o and o' being so disposed with relation to each other, that when one is in its operative

locking position, the other is in its releasing or unlocking position. That is to say, when the lock O is turned to the position shown in Fig. 2, the grate is locked against

5 movement in either direction, and the fuel supporting surfaces of the grate sections are horizontal and in proper position to correctly support the fuel without danger of having the projections on the grate sections 10 burned off. In this position the lever or handle may be freely inserted or removed from its socket in the bell crank, but when it is inserted and the lock O turned to the position shown in Fig. 3, the grate is released 15 and the lever or handle is locked in position by the engagement of the projection o' , in the recess m . The handle cannot be removed until the lock is again turned to the position indicated in Fig. 2 and consequently 20 it is impossible to remove the operating handle and leave the grate in an incorrect position, and it is equally impossible for the grate to be accidentally shifted or moved while the handle is removed, as, 25 for instance, by the engagement of a bar or implement with either the grate sections or the rocker bars during the cleaning of the fire or the removal of the ashes.

From Figs. 1 and 2 it will be seen that the 30 axis for each set of grate sections and the rocker bar on which they are mounted is located at approximately the center of the sections, while the sockets in the sections and the body portion of the rocker bar that 35 enters said socket are both located at one side of said axis. With this construction all of the advantages incident to the symmetrical arrangement of the faces of the grate sections about their axis are retained 40 and at the same time the metal of the bar engaging portions of the sections and of the body portions of the rocker bars is so disposed that the least possible obstruction to the flow of air occurs, and the greatest 45 strength is provided with the use of the least weight of metal. The normal angle of the body portion of the rocker bar is such that it is in the plane of movement of the air up through the grate and the air 50 passing up on each side of the body portion will keep both faces of the grate sections cooled, so as to prevent burning and distortion. In turning the sections for discharging ashes, the spaces between the grate sections 55 are maintained substantially uniform,

and the points of the sections will be caused to penetrate deeply and effectively into the body of material resting on the grate.

Having thus described my invention, what I claim as new and desire to secure by Letters Patent of the United States, is:

1. In a shaking grate for furnaces, the combination with the oscillating grate sections, a pivoted bell crank connected with said grate sections for oscillating the same, 65 an operating handle detachably connected with said crank said handle provided with a recess, means for locking the grate sections against oscillations and for preventing the removal of the handle when the grate 70 sections are out of normal position, consisting of a latch operative independently of the handle, pivotally mounted on the bell crank, a support for said bell crank having a recess whose walls coöperate with said 75 latch, and a projection on the latch extending into the recess in the handle when the latch is out of engagement with the walls of the recess, whereby the handle is secured to the bell crank, substantially as described. 80

2. In a shaking grate for furnaces, the combination with the oscillatory grate sections of substantially equilateral cross section, pivoted bell crank lever connected with said 85 grate sections, a locking latch pivoted on the bell crank above the axis, a support for the bell crank having a recess in which said latch engages when the grate sections are in normal position to lock the bell crank, a handle mounted removably in the bell crank 90 lever by which movement is imparted to the bell crank, said handle having a recess with which the latch engages when the grate sections are out of normal position preventing withdrawal of the handle. 95

3. In a furnace grate, the combination with the oscillatory grate sections, a rocker bar connected to said sections an arm pivotally connected to said bar having a series of 100 equally spaced openings therein, a link having a series of equally spaced openings at its inner end, the distance between centers of the holes in the two members being different and means for securing the members together through holes brought into registry. 105
